BATHROOM UNIT

Boris A. Krenov, New York, N. Y.

Application December 4, 1947, Serial No. 789,688

21 Claims. (Cl. 4-2)

1

This invention relates to bathroom fixtures, and more particularly to a unitary structure including a lavatory bowl, a flush tank, supply and drainage connections therefor, and supply and drainage connections for a bath tub and shower and drainage for a toilet.

It is well known that it requires much time, labor, skill and expense to install the several fixtures of a bathroom. Bathrooms, now being substantially standardized in equipment, it is the object of this invention to standardize a fixture that would be cheap, simple, convenient and easy to install. The fixture is designed to be all inclusive in its plumbing functions. The fixture is designed for use in a variety of types of bathroom constructions in buildings of various structure, old or new. The fixture can be used not only to serve one given bathroom but also to serve fixtures in an adjacent room or on upper or lower floors. An object of the invention, therefore, is the provision of a unit eliminating the numerous plumbing pipes, connections, fixtures and fittings and substituting for them one fixture. This fixture effects interconnection of a bath tub, a shower bath, a lavatory and toilet. The unit is in the form of a casting, in and through the block of which are put passages, conduits and/or channels which function in lieu of piping.

The main portion of the unit is a casting shaped to form a lavatory of a cabinet type. To one side of the casting is placed and connected a bath tub; to the other side is attached and connected a toilet bowl; on the top of the casting may be placed medicine cabinets, mirrors, towel racks, etc.

The upper portion of the casting forms a lavatory bowl and a streamlined projection which forms a shelf and a spout. The streamlined projection holds in its body the lever operating the lavatory drain valve and two faucets for hot and cold water. In the shelf of this streamlined projection is a depression forming a soap dish with a drain and six socket connections for the outside service pipes and one socket for the shower pipe. The upper portion of the casting also forms a flush tank at one side of the lavatory bowl. The flush tank is covered by a lavatory table top.

The casting, being shaped as a lavatory of cabinet type, has shelves, compartments and a hand grip which is an aid for getting into and out of the bath tub. Below the shelves are two compartments; one compartment is for storage purposes, the other compartment is a duct for

ventilation from which a low level intake high draught ventilation stack runs up through the height of the casting to draw out odors and moisture. The stack can be equipped with an electric exhaust fan which will increase the draught when needed. The edge of the bottom of these compartments is recessed to provide toe space so that a person may stand close to the front of the lavatory.

On the side of the casting to which is attached the bath tub is a streamlined projection which holds in its body the lever operating the bath tub drain valve, two faucets for hot and cold bath water and two faucets for hot and cold shower water. In the top of this streamlined projection is a depression forming a soap dish with a drain. In its lower part but above floor level the casting has two socket connections for the bath tub drain pipe and bath tub overflow pipe. On the other side of the casting below the flush tank is the nest for the toilet bowl and the connections for the flush discharge and for the toilet discharge.

On both sides of the toilet bowl are compartments for toilet paper, toilet articles, heater, etc.

In the accompanying drawings I have shown one embodiment of the invention. In this showing:

30 Fig. 1 is a perspective view of the fixture or unit showing it positioned in a bathroom and illustrating the position of a tub in dotted lines;

35 Fig. 2 is a plan view of the upper half of the casting showing the supply passages or conduits in dotted lines and omitting the drains and vents for clarity;

Fig. 3 is a plan view of the lower half of the casting showing the drains and vents;

Fig. 4 is a bottom plan view of the lower half of the casting;

Fig. 5 is a front elevation of the unit showing the supply channels and drains and vents in dotted lines;

Fig. 6 is a rear elevation;

Fig. 7 is a side elevation from the left side in Fig. 1;

Fig. 8 is a side elevation from the right side in Fig. 1;

Fig. 9 is a diagrammatic, perspective view of the supply lines; and

Fig. 10 is a similar view of the drains and vents.

Referring to the drawings the unit consists preferably of a lower casting 2 and an upper casting 4 with a table top 8 arranged on part of the upper casting. The castings may be made of

any suitable material and may be made in two or more parts. The castings are secured to each other in any suitable way depending upon the material from which they are made. They may be formed of cast metals, sheet metals, porcelain, glass, clay and various plastic compositions. A lavatory bowl 6 is formed in the upper casting and this bowl may be of any suitable shape, and it is contemplated that it will be of large size. The portion of the upper casting beneath the table 8 forms the flush tank 10 of the toilet. A toilet bowl 12 is attached to the lower casting and as shown may be set at an angle of substantially 45° to the front of the unit. A bath tub 14 is indicated in dotted lines in Fig. 1 of the drawings. The bath tub may be arranged as shown in the drawings or, depending upon the shape of the room, at right angles to the position shown. The unit may be either a right hand unit with the toilet bowl and tub arranged as shown, or may be constructed in the reverse of the illustrated embodiment with the positions of the toilet and tub reversed.

Conduits, forming supply lines for hot and cold water and providing drains and vents for the flush tank, the toilet, bath tub, shower and lavatory bowl, are cast or otherwise formed in the unit, thus eliminating the necessity of pipes and pipe connections except where the unit is connected to the outside sources of supply. These conduits or channels are illustrated separately in Figs. 9 and 10, Fig. 9 illustrating the supply lines and Fig. 10 illustrating the drains and vents. For purpose of illustration they are here shown in the form of tubes or pipes but the passages or channels are actually formed in the castings.

Thus, a hot water channel 16 extends through the upper casting terminating at the surface of shelf or projection 18 in the rear of the lavatory bowl and a similar cold water channel 20 is arranged adjacent to it. These channels extend through the upper casting only as shown in dotted lines in Fig. 6 of the drawings thereby providing for convenient pipe connections behind a recessed portion 21 (see Fig. 3) of the lower casting to pipes protruding through the floor or coming alongside the floor. Within the upper unit they run into other channels for feed of hot and cold water to the lavatory bowl, tub and shower and for delivery of cold water to the flush tank.

As shown in Fig. 9, the channels 16 and 20 are respectively connected to channels 22 and 24 running toward the front of the upper unit and, beneath these horizontal channels, the channels 16 and 20 are provided with cut-off cocks 26 and 28. These cocks serve to shut off the water supply for the purpose of making connections, cleaning and repairs. A pair of vertical channels 30 and 32 run into the horizontal channels 22 and 24. These channels extend to valve casings 34 and 36 arranged adjacent the front of the shelf or projection 18 at the rear of the lavatory bowl. The valve casings 34 and 35 are provided with valves having operating handles 38 and 40 mounted on the front face of the shelf 18. From the valve casings channels 42 and 44 extend to a spout or outlet 46 positioned at the top of the lavatory bowl as shown in Fig. 1.

Channel 24 runs into channel 48 which extends transversely of the upper casting and at one end runs into the flush tank 10. A cut-off valve 50 is arranged in this channel. A transverse channel 52 likewise runs into the hot water channel 22. These two channels extend upwardly as indicated by the reference numerals 54 and 56 into a pro-

jection 58 on the side of the unit over the bath tub. One set of valve casings 60 and 62, arranged within the projection 58, is connected to the bath tub spout 64 by channels 66 and 68. The valve casings are provided with valves arranged on the opposite faces of the projection 58 and having the usual handles 70 for operation (see Fig. 7). A second pair of valve casings 72 and 74 is also arranged within the projection 58 and these valve casings are connected to a channel 76 which extends horizontally of the unit toward the back and has its upper end 78 projecting through the upper surface of the shelf 18. Suitable piping may be connected to the end of this channel and to a shower bath head (not shown) arranged at the desired elevation over the tub. Valve casings 72 and 74 are likewise provided with valves projecting through the two faces of the projection 58 and provided with suitable handles 82 (see Fig. 7).

The flush tank is provided with the usual operating mechanism, the details of which are not herein shown, except to indicate, in dotted lines, the valve 84 (see Fig. 5) communicating with a flush channel 86 extending to the toilet bowl. This valve is operated in the usual manner by means of a valve handle 87 arranged on the exterior of the flush tank as shown in Fig. 5.

It will thus be apparent that when sources of hot and cold water are connected to the channels 16 and 20, water may be supplied to any of the component parts of the unit by operation of the usual control valves. The delivery of water may be made to other units in an adjacent room or on floors above or below through connections to the top and bottom conduits 16 and 20 or through connections to the branches 168 and 170 extending to the rear of the unit (see Fig. 6).

The unit also includes a system of drains and vents in the form of channels within the castings and suitably connected to the lavatory bowl, tub and toilet. These are shown diagrammatically in Fig. 10 of the drawings. Thus, the lavatory bowl 6 is provided with a drain comprising a conduit or channel 88 extending from the bottom of the bowl to a main conduit 90. A drain valve 92 is arranged in the conduit 90 and is connected by an operating rod 94 to the crank or eccentric portion of an operating shaft 96. This shaft projects from the front of the shelf 18 and is provided with an operating handle 98. The upper surface of the shelf 18 is provided with a depressed portion 100 forming a soap dish for the lavatory bowl. The bottom of the soap dish is provided with openings communicating with an individual drain channels 102 (see Fig. 10), which in turn communicates with the drain 90. A branch conduit 104 communicates by means of a separate channel 105 with the trap 108. This branch conduit has a spare connection 106 which is normally closed by a plug (see Fig. 6) to provide for connection of other fixtures or units in adjacent rooms. The lower end of the lavatory drain 90 communicates with trap 108, one end of which is provided with a removable cap 110 for access to the trap for cleaning. The trap is connected to a vent pipe 112 which is in turn connected to the soil stack channel 114 by a channel 116 which forms the lavatory drain discharge and by a second channel 117 arranged at a higher elevation forming a vent.

The bath tub drains and vents are shown to the right in Fig. 10 of the drawings. As shown in Figs. 1 and 7, a pair of socket connections 118 and 120 are arranged above the floor level, on the

side of the lower casting where the bath tub is positioned for connection to the bath tub drain pipe and the bath tub overflow pipe. The bath tub drain connection 120 communicates with a vertical channel 122 in which drain valve 124 is arranged. A valve rod 126 extends upwardly through the channel and is connected to the eccentric or crank portion of a shaft 128. This shaft is arranged in a horizontal channel 130 extending through the projection 58 and having an operating handle or lever 132 on its end arranged on the front of the projection as shown in Figs. 1 and 7. Also as shown in Fig. 1 the upper surface of the projection 58 is provided with a depressed portion 134 forming a soap dish for the bath tub. The soap dish is provided with openings 136 communicating with a channel 138 which in turn connects to the channel 130. The drain pipe connection 120 and the overflow pipe connection 118 communicate independently with a horizontal channel 138 which is connected to a drum trap 140. A spare connection 143 may also communicate with the channel 138 and this spare connection is normally closed by a plug or cover 144 on the rear of the lower casting (see Fig. 6). The trap 140 is provided with a removable cover 146 for cleaning out purposes. The outlet side of the trap is connected to a discharge channel 148 leading to the soil stack 114 and is also connected to a vent channel 150. This channel is connected to a cross channel 152, which in turn connects to the lavatory vent 112 and to the soil stack through the channel 117. This channel has two spare connections 164 which normally are closed with plugs or covers and which can be used for other fittings or for bathrooms in adjacent rooms or on upper or lower floors.

The toilet bowl drain is shown more clearly in Figs. 3 and 5. As shown, the bowl communicates with a trap 154 formed in the lower casting. The toilet bowl drain runs into the soil stack 114. The channels 148, connecting the soil pipe to vent channels 112 and 150, also serve as venting means in connection with discharge from the toilet bowl. The flush tank is provided with an overflow 156 (see Fig. 5), communicating with the flush channel 86.

The lower casting is provided with a horizontal channel 160 communicating with a vertical channel 162 which forms a ventilating duct. This duct may be extended by piping to the outside of the building and provided with a high velocity ventilating fan. This eliminates the necessity of windows in the bath room and thus permits the bath room to be situated in a part of the house not having a direct outlet to the exterior. As shown, the water supply conduits 16 and 20, the soil stack 114, the lavatory vent 112 and the bath vent 150 run vertically. This permits a series of units to be arranged on adjacent floors and connected to each other by piping from the top of one unit to the bottom of the next. Flow of water below the bottom unit of a series is prevented by closing cocks 26 and 28. The upper ends of the vents 112 and 150 and of the soil stack 114 are, of course, connected to suitable piping extending to the exterior. Various conduits may also be provided with horizontally arranged spare connections to the conduits for the purpose of connecting a unit to toilet facilities in an adjacent room on the same floor. Such connections to drum trap 140 and to the lavatory overflow have heretofore been described and are illustrated in Fig. 7. A spare connection from vent 150 may extend to the rear of the upper casting and is

normally closed by a plug or cover 164. A spare connection from the lavatory vent 112 may likewise extend to the rear of the upper casting and is normally closed by a plug or cover 166. A spare connection from the lavatory overflow may likewise extend to the rear of the upper casting and is normally closed by a plug or cover 106. The hot and cold water channels 16 and 20 may be provided with connections extending to the rear of the upper casting and normally closed by plugs 168 and 170. A spare connection to the lavatory trap may extend to the rear of the upper casting and is normally closed by a plug 172. A spare connection from the bath discharge may extend to the rear of the lower casting and is normally closed by a plug 144. A spare connection from the soil stack may extend to the rear of the lower casting and is normally closed by a plug 176.

At the front of the lower casting below the lavatory bowl I preferably provide a shelf 178 for sponges, etc., and this shelf is provided with an opening 180 at the side to permit access to it from the tub. The provision of this opening also provides a portion 182 which serves as a sturdy hand grip when getting in and out of the tub. Beneath the shelf 178 I provide a series of shelves 184 for towels, toilet articles, etc. In the space below the lower shelf 184, not occupied by the ventilating duct 160, I provide an additional shelf 186. Also in the lower casting below the flush tank at the one side of the toilet below the space which would otherwise be unoccupied is formed a shelf 188.

On the side of the unit beyond the toilet bowl I also provide a series of compartments (see Fig. 3). In the upper of the two compartments adjacent the toilet bowl shown at 190 may be arranged a suitable holder for toilet paper and the compartment 192 immediately below it may be utilized for the storage of toilet paper. The compartment 194 may be utilized for the provision of an electric heater.

Above the unit I may provide suitable mirrors, lighting fixtures, towel racks, etc. The end of the upper casting over the compartments 194 may be provided with suitable holders or sockets 196 (see Fig. 5) for towel rods 198, the other ends of which may be secured in sockets or holders 200 in the end wall of the bath room.

In addition to the advantages of the invention which are apparent from the preceding description, attention is called to the fact that all of the conduits are straight lines and are therefore easy to manufacture and easy to clean. The ends of the conduits or channels are threaded either for connection to outside pipes or to the other parts with which they cooperate. The castings are made to require as little machining as possible and can be cast from cheap materials such as cast iron. The provision of the channels through the material of which the casting is made eliminates the use of numerous pipe joints and therefore the possibility of leaks.

Although I have illustrated and described a preferred embodiment of the invention, it is of course understood that various changes may be made within the scope of the appended claims.

I claim:

1. A bath room fixture comprising a substantially solid unit having a series of passages therein to form hot and cold water supplies to a tub and lavatory bowl and a cold water supply to a flush tank, and having a second series of passages therein to form drainage for the tub, lavatory bowl and a toilet.

2. A bath room fixture comprising a substantially solid unit having a series of passages therein to form hot and cold water supplies to a tub, a lavatory bowl and a cold water supply to a flush tank; and having a second series of passages therein to form drainage for the tub, lavatory bowl, flush tank, and a toilet bowl; and having a third series of passages for venting.

3. A bath room fixture comprising a substantially solid unit having a lavatory bowl in the top thereof, a toilet arranged on one side of the unit, and control fixtures for supply and drainage of a bath tub arranged on the other side of the unit, the unit being provided with a series of channels to form hot and cold water supplies to the lavatory bowl and the tub fixture and a cold water supply to the toilet, and the unit being further provided with a series of passages to form drainage for the tub, bowl and toilet.

4. A bathroom fixture comprising a substantially solid unit having a lavatory bowl supply and drainage control fixtures for the lavatory bowl in the top of the fixture, a flush tank formed in the fixture, supply and drainage control fixtures for the flush tank, a toilet arranged on one side of the unit, control fixtures for supply and drainage of a bath tub and shower arranged on the other side of the unit; the unit being provided with a series of passages to form hot and cold water supplies to the tub and shower fixtures and to the lavatory bowl and a cold water supply to the flush tank, the unit being further provided with a series of passages to form drainage for the tub, lavatory bowl, flush tank and toilet and having a third series of passages for venting.

5. A bath room fixture comprising an upper and a lower casting, the upper casting being provided with passages to form hot and cold water supplies to a tub, a lavatory bowl and a cold water supply to a flush tank, and the two castings being provided with passages to form drainage for the tub, lavatory bowl, flush tank and toilet and the two castings being provided with a series of passages for venting.

6. A bath room fixture comprising a unit having a lavatory bowl in the top, a spout above the bowl, a spout on one side of the unit to deliver water to a bath tub arranged beside the unit, the unit being provided with supply passages to deliver hot and cold water to the spouts, being further provided with drainage passages for the bowl, the drainage passages within the unit adapted to be connected to the bath tub drain, and venting means within the unit.

7. A bath room fixture comprising a substantially solid unit having a lavatory bowl therein and having a toilet flush tank within the unit, a toilet arranged on the unit, supply passages in the unit to supply hot and cold water to the lavatory bowl and cold water to the flush tank, drainage passages in the unit connected to the lavatory bowl, the flush tank and the toilet, and venting passages in the unit.

8. A bath room fixture comprising a substantially solid unit having a lavatory bowl, an extension arranged on one side of the unit adapted to be positioned over a bath, a drainage connection on the side of the unit beneath the extension adapted to be connected to a bath tub drain and to a bath tub overflow, supply passages in the unit for hot and cold water connected to the lavatory bowl and to the extension, drainage passages in the unit connected to the lavatory bowl and to the drainage connection and venting passages in the unit.

9. A bath room fixture comprising a substantially solid unit having a passage therein forming a soil stack and having passages forming vents and connected to the soil stack, a lavatory bowl in the top of the unit, a drainage passage between the lavatory bowl and the soil stack, a toilet arranged on one side of the unit, a drainage passage between the toilet and the soil stack, a drainage passage on the other side of the unit connected to the soil stack, said passage being adapted to be connected to the drain of a bath tub arranged beside the unit.

10. A bath room fixture comprising a substantially solid unit having a lavatory bowl in the top and a flush tank in the unit and having a series of passages therein to form hot and cold water supplies to the bowl, to a tub and shower, and cold water supply to a flush tank, having a second series of passages therein to form drainage for the tub, lavatory bowl, flush tank and toilet, and having a third series of passages therein to form venting.

11. A bath room fixture comprising a substantially solid unit having a flush tank within the unit and a toilet arranged at one side thereof and having a series of passages therein to form hot and cold water supplies to a tub and shower and to the lavatory bowl and a cold water supply to the flush tank, having a second series of passages therein to form drainage for the tub, bowl, flush tank and toilet, and having a third series of passages therein to form venting.

12. A bath room fixture comprising a substantially solid unit having a lavatory bowl in the top thereof, having a flush tank within the unit and a toilet arranged at one side, and having a series of passages therein to form hot and cold water supplies to the lavatory bowl and to a tub and shower, and a cold water supply to the flush tank, having a second series of passages therein to form drainage for the tub, bowl, flush tank and toilet and having a third series of passages therein to form venting.

13. A bath room fixture comprising a substantially solid unit having a flush tank within the unit and a toilet arranged on one side of the unit, and having control fixtures for supply and drainage of a bath tub and shower on the other side of the unit, the unit being provided with a series of passages to form hot and cold water supplies to the control fixtures and a cold water supply to the flush tank, the unit being provided with a series of passages to form drainage for the tub, flush tank and toilet, and the unit being further provided with a series of passages for venting.

14. A bath room fixture comprising upper and lower castings, a lavatory bowl and a flush tank formed in the upper casting, the upper casting being provided with passages to form hot and cold water supplies to the lavatory bowl and to a bath tub and shower and a cold water supply to the flush tank, and the two units being provided with passages to form drainage for the lavatory bowl, flush tank, tub and toilet, and the unit being further provided with a series of passages for venting.

15. A bath room fixture comprising upper and lower castings, the upper casting having a lavatory bowl and a flush tank in the top thereof, a toilet arranged at one side of the lower casting, the upper casting being provided with passages to form hot and cold water supplies to the lavatory bowl, to a tub and shower, and a cold water supply to the flush tank, and the two units being provided with passages to form drainage for the

lavatory bowl, the flush tank, tub and toilet and the unit being further provided with a series of passages for venting.

16. A bath room fixture comprising upper and lower castings, the upper casting having a lavatory bowl in the top thereof and a flush tank at one side thereof, control fixtures for a bath tub and shower arranged on the other side of the upper unit, a toilet on the side of the lower unit below the flush tank, the upper casting being provided with passages to form hot and cold water supplies to the lavatory bowl and to the tub and shower fixtures, and a cold water supply to the flush tank, the two units being provided with passages to form drainage for the lavatory bowl, flush tank, tub and toilet, and the unit being further provided with a series of passages for venting.

17. A bath room fixture comprising a unit having a lavatory bowl in the top thereof, a toilet arranged on one side of the unit, a flush tank within the unit adjacent the toilet, the unit having a series of passages therein to form hot and cold water supplies to the lavatory bowl and a cold water supply to the flush tank, and having a second series of passages therein to form drainage for the bowl, flush tank and toilet, and the unit being further provided with a series of passages for venting.

18. A bath room fixture comprising a unit having a lavatory bowl in the top thereof, a toilet arranged at one side of the unit, and control fixtures for supply and drainage of a bath tub and shower arranged on the other side of the unit, a flush tank in the unit, the unit being provided with a series of passages to form hot and cold water supplies to the lavatory bowl and the tub and shower fixtures, and a cold water supply to the flush tank, and the unit being provided with a series of passages to form drainage for the tub, bowl, flush tank and toilet, and the unit being further provided with a series of passages for venting.

19. A bath room fixture comprising a unit having a lavatory bowl and flush tank in the top thereof, a toilet arranged on one side of the unit, an extension arranged on the other side of the unit adapted to be positioned over a bath tub,

5 a drainage connection on the side of the unit beneath the extension adapted to be connected to a bath tub drain and bath tub overflow, supply conduits in the unit for hot and cold water to the lavatory bowl and to the extension, and a conduit for cold water to the flush tank, and drainage conduits in the unit to the lavatory bowl, flush tank toilet and to the drainage connection, and conduits in the unit for venting purposes.

10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

20. A bath room fixture comprising a unit having a passage therein forming a soil stack, and having passages forming vents connected to the soil stack, and having a series of passages therein to form hot and cold water supplies to a tub, shower and lavatory bowl, and a cold water supply to a flush tank and having another series of passages therein to connect the tub, bowl and toilet to the soil stack and to the vent channels.

21. A bath room fixture comprising a unit having a lavatory bowl and a flush tank in the top thereof, a toilet arranged on one side of the unit, and control fixtures for supply and drainage of a bath tub and a shower arranged on the other side of the unit, the unit having a passage therein forming a soil stack and having passages forming vents connected to the soil stack, the unit being provided with a series of passages to form hot and cold water supplies to the lavatory bowl and the tub and shower fixture, and a cold water supply to the flush tank, and the unit being further provided with another series of passages connecting the lavatory bowl, toilet and tub to the soil stack and to the vent passages.

BORIS A. KRENOV.
